UNITED STATES PATENT OFFICE

STIRLING TOMKINS, OF SOUTH NYACK, NEW YORK

BELT

Application filed June 30, 1928. Serial No. 289,361.

This invention relates to belts, and the particular embodiments of the invention here shown comprise material conveying and draining belts, although the invention in certain of its phases has broader aspects.

The objects of the invention include the provision of a simple, durable and relatively inexpensive belt construction of the above indicated class. Further and more specific objects, features and advantages will more clearly appear from the detailed description given below taken in connection with the accompanying drawings which form a part of this specification.

The invention consists in the novel features, arrangements and combinations of parts and materials embodied by way of example only in the constructions herein described, as illustrative of preferred embodiments.

In the drawings, Fig. 1 is a sectional view through a belt construction embodying the invention and showing the belt in operative position in relation to conveyor pulleys or rollers;

Fig. 2 is a top plan view of the embodiment as of Fig. 1; and

Figs. 3 and 4 are similar to Fig. 1, but illustrate additional embodiments of the invention.

Referring to Fig. 1, the construction there shown may comprise a central band or belt portion 10, preferably formed of relatively thin sheet metal of great tensile strength, as for example sheet steel. At each side of the belt portion 10, I preferably provide supplemental belt strips 11 formed of fabric, leather, rubber, combinations of these materials, or other readily flexible compositions secured flatwise to the edges of the portion 10. Conveyor rollers arranged in a well known manner are indicated at 12 and 13.

Referring to Fig. 2, it will be noted that the metallic belt portion 10 is formed with a multitude of closely spaced perforations 14, which permit moisture or other liquids to be drained away from the material which is carried on the conveyor. These perforations may be of such dimensions and so spaced, taking into consideration the fineness of the

material conveyed, that the material will not drop through nor become clogged in the perforations so as to preclude proper draining. Inasmuch as the belt portion 10, being of metal, may be made of great strength and yet be relatively thin, the perforations through such thin relatively rigid material, within reasonable limits, have no tendency to become clogged. That is, particles of material are either small enough to drop freely through such perforations, or else are of sufficient size so that they do not enter the perforations. On the other hand, it will be appreciated that if similar perforations were made in relatively thicker and more yielding material, particles of material would much more readily become clogged between the more extended walls of the perforations and also with such material the area of the perforations would vary with varying tensions and loads and flexure of the belt, so that particles would be admitted to the perforations and caught therein before dropping through. I find that these difficulties are substantially obviated with the use of the perforated thin metal belt above described.

In order that the edges of the belt portion 10 may be of substantially maximum strength, I find it preferable to leave a blank unperforated portion along each edge, as at 15. Also, at intervals of say twenty-five feet along the length of the belt, I find it desirable to leave a blank unperforated space as at 16, several inches in width, so as to permit the belt material to be readily cut up into sections and joined as by riveting substantially without diminishing its strength. The flexible side portions 11 are shown fastened to the portion 10 by rivets at 17.

With this construction large masses of heavy materials may be carried by a conveyor belt relatively light in weight and of exceptional durability. By using the highly flexible flange portions 11, longitudinal flexure of the load carrying metal portion 10 is avoided. Also the portions 11 may be readily made of any desired degree of flexibility and without interfering with the load carrying capacity of the portion 10. If desired the portions 11 may be of relatively inexpensive

sive material and renewed from time to time, while the portion 10, if made of steel, may be used for long periods of time even for handling rough stone or other materials which 5 quickly destroy many types of conveyor belts by abrasive action.

It will be understood that the relative widths and proportions of the strips 10 and 11 may be varied within wide limits to provide the desired conveyor capacity, the steel portion 10 being of sufficient strength to comply with an unusually wide range of requirements.

In the embodiment of the invention shown 15 in Fig. 3, a pair of steel belt portions are indicated at 18, joined along the mid portion of the belt by a fabric or other flexible member 19. The portions 18 are supported upon conveyor rollers as at 20 at suitable angles to 20 provide the desired troughing to give the necessary capacity and draining properties.

In Fig. 4 an embodiment of the invention 25 is shown in which the central portion of the belt comprises a pair of metallic strips as at 22 and 23 connected by a flexible piece 24, and provided at each side with flexible troughing strips 25. Belts of a desired large capacity 30 may be built up in this way from standardized belt portions, such as used in the embodiment of Fig. 1.

In all of the embodiments it will be observed that the metallic load carrying portions, whether perforated or not, may be used without longitudinal bending thereof except 35 for the usual slight crowning curvature, as indicated on the conveyor pulleys 12 and 27.

A belt of the desired length may be made 40 by riveting together the ends of one or more sections of the middle portions as at 10, 22 and 23 as above suggested. The more flexible portions as at 11, 25, etc., may if desired also be riveted or secured together at their ends, or the ends thereof may be merely left 45 in overlapping or substantially abutting relation.

While the invention has been described in detail with respect to certain preferred examples thereof which give satisfactory results, it will be understood by those skilled in 50 the art after understanding the invention, that various changes and modifications may be made without departing from the spirit and scope of the invention and it is intended therefore in the appended claim to cover all 55 such changes and modifications.

What is claimed as new and desired to be secured by Letters Patent of the United States is:

A belt for conveying and draining material 60 comprising an elongated flexible sheet metal perforated load-carrying portion extending integrally a substantial distance in the direction of movement of the belt, and additional strips of material of relatively greater flexibility extending along and secured to each

edge thereof and adapted to be flexed to variable degrees from the plane of said load-carrying portion for forming therewith a conveying trough.

In testimony whereof I have signed my 70 name to this specification.

STIRLING TOMKINS.
